[57] CLAIM

The ornamental design for an electrically controlled battery driven jack, as shown and described.

DESCRIPTION

FIG. 1 is a perspective view of a first embodiment with a flat bottom and the reverse side the same as the near side;

FIG. 2 is a perspective view of a second embodiment with a flat bottom and the reverse side the same as the near side; and,

FIG. 3 is a perspective view of a third embodiment with a flat bottom and the reverse side the same as the near side. The broken lines in the figures are for illustrative purposes only and form no part of the claimed design.

The cord is shown broken away in the figures to show indefinite length.
